UNITED STATES PATENT OFFICE.

FRANK McINTYRE, OF NEW YORK, N. Y., ASSIGNOR TO EAGLE PENCIL COMPANY, OF NEW YORK, N. Y., A CORPORATION.

DESIGN FOR AN ERASER-TIP.

No. 38,038.

Specification for Design.

Patented May 29, 1906.

Application filed April 13, 1906. Serial No. 311,600. Term of patent 14 years.

To all whom it may concern:

Be it known that I, FRANK McINTYRE, a citizen of the United States, and a resident of New York city, in the county and State of New York, have invented a new, original, and ornamental Design for Eraser-Tips for Lead-Pencils, Penholders, Pencil-Point Protectors, and the Like, of which the following is a specification.

o This invention relates to metallic tips designed to be applied to lead-pencils, penholders, pencil-point protectors, and the like and to hold erasive material.

The accompanying drawing is a perspective view of my new design for eraser-tips somewhat exaggerated in size, so that the nature of the design may be better appreciated.

As shown in the drawing, it consists of an outer tube adapted to receive and hold at one end the erasive material which is represented in that end.

The portion of the tube unoccupied by the erasive material is circumferentially slotted,

there being as many of such slots as there are color-bands to be displayed, these slots being separated from one another by narrow continuous rings and bridged at intervals by narrow connecting-strips, the strips and rings being integral with the tube. Within the slotted portion of the tube is inserted a close-fitting metallic lining of a color contrasting with that of the exterior of the outer tube. The effect produced is to invest the tube with circumferential bands of a color contrasting with that of the body of the tube, which bands appear as slightly sunken below the outer surface of the tube and as bridged at intervals by narrow strips forming part of the body of the tube.

I claim—

The ornamental design for an eraser-tip, as herein shown and described.

FRANK McINTYRE.
